UNITED STATES PATENT OFFICE

2,474,745

MINNOW BUCKET

John B. Lewis, Indianapolis, Ind.

Application June 21, 1947, Serial No. 756,129

7 Claims. (Cl. 43—56)

1

This invention relates to a minnow bucket and has for a primary object the provision of means for delivering a limited number of minnows at a time through at least one side door of the bucket. A further object of the invention is to provide a structure wherein the minnows may be lifted out of the water in the bucket and delivered through an upper side door with the minimum amount of handling; and further be delivered directly into the hand of the fisherman held immediately around the door. Other important objects of the invention reside in the unique features of the construction as included in the appended claims, such other objects becoming more apparent to those versed in the art in the following description of the one particular form of the invention as illustrated in the accompanying drawings, in which

Fig. 1 is a view in central vertical section through a minnow bucket embodying the invention;

Fig. 2 is a detail in outside elevation of a door in closed position on the bucket;

Fig. 3 is a central vertical section through the upper portion of the bucket on the line 3—3 in Fig. 1;

Fig. 4 is a detail in vertical section on the line 4—4 in Fig. 1;

Fig. 5 is a horizontal section on the line 5—5 in Fig. 1 with the structure revolved 90 degrees from the position indicated in Fig. 1;

Fig. 6 is a view in perspective of a detached door structure, and

Fig. 7 is a view in perspective of a modified form of the door structure.

Referring to the drawings in which like characters of reference indicate like parts, a minnow bucket 10 of the usual form is provided having perforations 11 around its upper portion. An upper closure 12 is provided having the usual lid 13, opening of which permits access to the inside of the bucket 10. A bail 14 is provided as a means for lifting and carrying about the bucket.

At diametrically spaced positions are secured to the under side of the closure 12, nipples 15 and 16, serving as guides for the posts 17 and 18 slidingly carried therethrough, and through the closure 12 to have a bail 19 interconnect their upper ends. Each of these posts 17 and 18 are interconnected across their lower ends by a bar or plate 20. The outer ends of the bar 20 are slidingly guided between vertically disposed channel guides 21 and 22 which are secured to the side wall of the bucket 10.

An elongated, perforated or foraminous basket

2

23 herein shown as formed out of wire screen material is centrally mounted on and carried by the bar 20. The floor 60 of this basket 23 slopes downwardly from each side of the bar 20 in opposite directions toward the side wall of the bucket 10, and is wider at that portion immediately about the bar 20. The basket 23 has vertically disposed side walls 24 and 25, the outer ends of which adjacent the wall 10 on each side thereof are spaced to equal substantially the width of the diametrically opposed openings, 26 and 27 through the side wall of the bucket 10.

Normally, the basket 23 drops by gravity to the lowermost position as indicated by dash lines in Fig. 1 where the down-turned lips 137 and 28 under the outer ends of the basket 23 rest on the floor 29 of the bucket.

By lifting the bail 19 the basket 23 is carried to the upper portion of the bucket 10 to the upper limit as determined by the shoulders 30 and 31, Fig. 3, provided around the posts 17 and 18, the shoulders 30 and 31 striking respectively the under sides of the members 15 and 16. When in this position, the open ends of the basket 23 register respectively with the bucket side openings 26 and 27.

As indicated in Fig. 2, each of these openings 26 and 27 is closed respectively by doors 32 and 33 normally held in closed position by means of torsion springs 34 and 61 respectively. Figs. 1 and 2.

The doors may be provided in a form which will cause the doors to automatically open at lifting of the basket 23 to its extreme upper position, or the door may remain closed and be opened manually. Both forms are herein shown, Figs. 6 and 7, Fig. 6 illustrating a structure attached to the door 33 which will permit the door to remain closed regardless of travel of the basket 23, whereas in Fig. 7, the door 32 has a structure attached thereto causing it to open automatically by travel of the basket 23.

Referring to the door 32, it is hinged along its lower end by the pin 35 through ears 36 and 37 fixed on the bucket 10 so that the door 32 has to be swung upwardly to a vertical position to close the opening 26. On each side of the door are metal side plates 38 and 39 respectively with their outer edge rounded so that these plates 38 and 39 may swing through the opening 26 inside of the bucket 10 to permit the door 32 to close. The upper edges of these plates 38 and 39 are interconnected by a curved plate 40. This plate 40 terminates by an outer edge 41 at a distance 55 from the door 32 as an opening through which

minnows may be dropped in a controlled manner, that is, so that they cannot flop over the side plates 38 and 39. Then there are side wings 42 and 43 turned at right angles from the side plates 38 and 39 respectively to serve as stops to strike the inside wall of the bucket 10 when the door 32 is in substantially a horizontal position, Fig. 1. Furthermore the curved plate 40 continues on around from the side plates 38 and 39 to be in the path of the side walls 24 and 25 of the basket 23, the length of this overhanging portion of the length 40 being sufficient that when the door 32 is in a closed position, the lifting of the basket 23 will cause the side walls 24 and 25 to strike the plate 40 and thus rock the door 32 outwardly and into its lowermost position, Fig. 1.

The other type of door 33 carries the side plates 44 and 45 between which a short length of a curved plate 46 is mounted, terminating by an outer edge 47 to leave space between it and the door 33 for minnows to feed out therebetween. The other end portion of the plate 46 is provided with a central tongue 48 between the sides 44 and 45 to leave spaces or slots 49 and 50 between the tongue and the respective side walls. The vertical edges (door in horizontal position) of the plates 44 and 45 are provided with the ears 51 and 56 to strike the inside of the wall of the bucket 10 to maintain the door 33 in substantially a horizontally disposed position.

In reference to the door 33, assuming it to be in the closed position, Fig. 1, the bucket 23 may be raised to its upper limit which will bring the basket walls 24 and 25 into the slots 49 and 50 without in any way causing the door 33 to move. Then the door 33 may be pulled open and the minnows on the inclined surface of the basket immediately back of the door will slide down and out through the opening between the door and the edge 47. The curved plates 40 and 46, in each instance serve to confine the minnows to the restricted space over the respective doors.

While the invention has been described in the one particular form in detail, it is obvious that structural variations may be embodied without departing from the spirit of the invention and I therefore do not desire to be limited to that precise form beyond the limitations which may be imposed by the following claims.

I claim:

1. A live bait container comprising a bucket; a basket carried therewithin; members shiftable vertically of the bucket for lifting and lowering said basket; said basket having at opposite sides restricted openings therefrom at the floor level of the basket; said basket having side openings coinciding with said basket openings when the basket is in an uppermost position; and a door over each of said basket openings hinged to open outwardly and downwardly to form discharge chutes from said basket openings.

2. A live bait container comprising a bucket; a basket carried therewithin; members shiftable vertically of the bucket for lifting and lowering said basket; said basket having at opposite sides restricted openings therefrom at the floor level of the basket; said basket having side openings coinciding with said basket openings when the basket is in an uppermost position; and a door over each of said basket openings hinged to open outwardly and downwardly to form discharge chutes from said basket openings; said doors having side members, a floor member and a cover member between the sides forming said chutes.

3. A live bait container comprising a bucket;

a basket carried therewithin; members shiftable vertically of the bucket for lifting and lowering said basket; said basket having at opposite sides restricted openings therefrom at the floor level of the basket; said basket having side openings coinciding with said basket openings when the basket is in an uppermost position; and a door over each of said basket openings hinged to open outwardly and downwardly to form discharge chutes from said basket openings; said doors having side members, a floor member and a cover member between the sides forming said chutes; at least one of said door cover members extending from the top portion of said basket when the doors are in an open position.

4. A live bait container comprising a bucket; a basket therein; members for lifting and lowering said basket toward the top and bottom of the bucket; said basket having sides and a floor therebetween inclined downwardly toward and terminating in close proximity to the wall of the bucket, the basket having an outer end opening from over said floor between said sides; said bucket having an opening through its sides to coincide with said basket opening when the basket is in an elevated position; and a door normally closed over said bucket opening, hinged to open downwardly to be an extension of the floor of said basket.

5. A live bait container comprising a bucket; a basket therein; members for lifting and lowering said basket toward the top and bottom of the bucket; said basket having sides and a floor therebetween inclined downwardly toward and terminating in close proximity to the wall of the bucket, the basket having an outer end opening from over said floor between said sides; said bucket having an opening through its sides to coincide with said basket opening when the basket is in an elevated position; and a door normally closed over said bucket opening, hinged to open downwardly to be an extension of the floor of said basket; and a member carried by said door extending inwardly therefrom relative to the closed door position to be in the path of said basket, whereby upward travel of the basket will carry it against said door member and rock the door to an open position.

6. A live bait container comprising a bucket; a basket therein; members for lifting and lowering said basket toward the top and bottom of the bucket; said basket having sides and a floor therebetween inclined downwardly toward and terminating in close proximity to the wall of the bucket, the basket having an outer end opening from over said floor between said sides; said bucket having an opening through its sides to coincide with said basket opening when the basket is in an elevated position; and a door normally closed over said bucket opening, hinged to open downwardly to provide a floor extension of the floor of said basket; and a member carried by said door extending inwardly therefrom relative to the closed door position to be in the path of said basket, whereby upward travel of the basket will carry it against said door member and rock the door to an open position; said door member comprising a hood spaced from the floor extension.

7. A live bait container comprising a bucket; a basket carried therewithin; members shiftable vertically of the bucket for lifting and lowering said basket; said basket having at opposite sides restricted openings therefrom at the floor level of the basket; said basket having side openings coinciding with said basket openings when the basket is in an uppermost position; and a door over each of said basket openings hinged to open outwardly and downwardly to form discharge chutes from said basket openings; said doors having side members, a floor member and a cover member between the sides forming said chutes; at least one of said door cover members extending from the top portion of said basket when the doors are in an open position.

basket is in an uppermost position; and a door over each of said bucket openings hinged to open outwardly and downwardly to form discharge chutes from said basket openings; said basket being of elongated nature and of less transverse area than that of the bucket, and said basket further having its floor sloped respectively downwardly from a center zone toward each of its said sides.
